VACUUM TUBE CIRCUIT

Alphons V. Wurmser, Teaneck, N. J., assignor to
Bell Telephone Laboratories, Incorporated,
New York, N. Y., a corporation of New York

Application August 18, 1933, Serial No. 685,696

7 Claims. (Cl. 178—44)

This invention relates to vacuum tube circuits, as for example vacuum tube amplifiers.

Objects of the invention are to control phase and amplitude of waves in such circuits.

5 It is also an object of the invention to so control phase and amplitude of waves as to reduce singing tendency in vacuum tube amplifiers that feed back modulation or distortion components for reducing distortion, or feed back fundamental components for increasing stability, or both. Such amplifiers are disclosed, for example in a copending application of H. S. Black, Serial No. 411,223, filed December 3, 1929, for Wave translation systems, and in British Patent 317,005.

10 15 Certain terms and symbols used herein have the following significance. Singing refers to operation such that an impressed small disturbance which itself dies out results in a response that does not die out but goes on indefinitely, either 20 staying at a relatively small value or increasing until it is limited by the non-linearity of the system. The amplification of a vacuum tube amplifier without feedback is designated μ and is the 25 complex quantity by which the voltage on the grid of the first tube must be multiplied by to obtain the phase and magnitude of the total resulting voltage in the plate circuit of the last tube. Amplification ratio is the absolute or scalar value of μ . Gain is twenty times the logarithm of the 30 amplification ratio. The quantity $\mu\beta$ represents the propagation once around the closed feedback loop of a feedback amplifier. It follows that β designates the complex quantity by which a driving 35 voltage in the space path of the last tube, in series with the plate-filament impedance in that tube, must be multiplied to give the voltage that it—the driving voltage alone—acting through the feedback path, will produce on the grid of the first tube. As shown in a copending application 40 of H. S. Black, Serial No. 606,871, filed April 22, 1932 for Wave translation systems, the amplification of a feedback amplifier is

$$\frac{\mu}{1-\mu\beta}$$

45 and the corresponding change in amplification caused by the feedback action is

$$\frac{1}{1-\mu\beta}$$

50 The quantity

$$\frac{1}{1-\mu\beta}$$

55 is a quantitative measure of the amount of feed-

back, and herein, as in that application, the feed-back is described as positive feedback or negative feedback according as the absolute value of

$$\frac{1}{1-\mu\beta}$$

is greater or less than unity.

In one specific aspect the invention is embodied in vacuum tube amplifiers of the general type in which waves including those of the range of transmitted frequencies, are so fed back from the output to the input as to reduce the gain of the amplifier below the value that it would have without feedback in order to reduce unwanted modulation or non-linear effects and render the gain 10 15 stability greater than it would be without feedback. That type of amplifier is disclosed for example in the above mentioned copending applications and in the above mentioned British patent, and in British Patents 371,887 and 374,130. 20

In such amplifiers, where tube modulation reduction for modulation components of given frequencies is to be large, it is proportional to the gain, (for those modulation components) in a single trip around the closed feedback loop and consequently that gain should be large. The modulation components that it is desired to reduce by feedback are usually waves of frequencies within the utilized frequency range, e. g. within the range of the frequencies of the 30 signal waves to be amplified by the amplifier. In practice, when the loop gain (i. e., the decibel gain for a single trip around the loop) is large for the frequencies of the utilized frequency range, it is greater than zero for some 35 higher frequency and for some lower frequency and if the loop phase shift (i. e. the phase shift experienced by waves in passing once around the loop) is zero or a multiple of 360° for any frequency at which the loop gain equals or exceeds zero decibels, the amplifier may sing at that frequency. (As indicated in the above mentioned copending application, Serial No. 606,871, a criterion for freedom from singing is given by Nyquist's rule, in his article on "Re- 40

45 generation theory", Bell System Technical Journal, January, 1932, pages 126 to 147. Such criterion is given also in the above mentioned British Patent 374,130.) Moreover, passive networks introduced in the loop to contribute a component of loop attenuation increasing with frequency ordinarily introduce a component of loop phase shift that tends to lower the frequency, and raise the gain, at which the loop phase shift reaches a given multiple of 360° . To avoid the 55

singing condition, it is desirable to control the loop phase shift and the loop gain carefully with respect to the entire frequency spectrum. (Such control is desirable also for other reasons, as for example to prevent loop phase shift from causing increase in the gain of the amplifier, which increase may be undesirable because accompanied by a corresponding increase in the modulation products. This increase in gain may become a limiting factor determining the permissible loop phase shift at high frequencies where it becomes difficult to obtain sufficient feedback. At other frequencies it is usually not a limiting factor. For example, assuming the amplifier does not sing, the amplifier gain change produced by feedback will be within 1 decibel of the gain around the feedback loop regardless of phase shift if the gain around the loop exceeds 20 decibels. Further, the feedback does not increase the amplifier gain if the loop gain exceeds 6 decibels.) If the value of the loop phase shift were maintained at $\pm 180^\circ$ it would be as remote as possible from the potential singing values of 0° and multiples of 360° ; however, in practice it is not necessary to attain this condition. The requirement for freedom from singing will always be met if for every frequency of loop gain, (i. e., every frequency at which the loop gain is zero or greater) the loop phase shift differs from zero and every multiple of 360° , or in other words if the loop phase shift frequency characteristic does not cross nor touch the zero phase shift axis in the frequency range of loop gain. (It is not to be inferred that this requirement is always essential for freedom from singing. A criterion for such freedom is given by Nyquist's rule, as referred to above.)

In designing an amplifier with negative feedback for distortion reduction, assuming the vacuum tube or tubes of each stage in the loop to introduce a phase shift having a constant component of 180° (in addition to any component due to interelectrode capacitance, for example), the number of vacuum tube stages used in the loop may be made either odd or even, to facilitate control of singing tendency. The question whether an odd or an even number is more suitable will depend upon whether the loop is made to have phase reversing means other than the tubes, and upon what other phase shifts are present in the loop. If, over the frequency range of loop gain the constant component of the total loop phase shift is any odd multiple of 180° , then it is necessary that the total variation of the loop phase shift with frequency over that frequency range be maintained within limits of $+180^\circ$ and -180° in order to make the total loop phase shift differ from zero and every multiple of 360° for every frequency in that frequency range.

The difficulty of insuring that the variation of loop phase shift with frequency is maintained within the required limits over the frequency range of loop gain is in general increased by the fact that, (as brought out, for example, in the above mentioned copending application), when the distortion reduction and associated amplifier gain reduction produced by feedback action is to be large, the gain of the amplifier without feedback must then correspondingly exceed the gain required with feedback; because when the gain without feedback, required to produce the desired amount of distortion reducing feedback and the desired amount of gain with feedback, necessitates use of a plu-

rality of stages and a plurality of interstage coupling circuits, the phase shifts around the closed loop may become large at low frequencies or high frequencies, or both, especially at frequencies well below or well above the utilized range. For example, the phase shifts may become large at low frequencies because of interstage coupling condensers, and at high frequencies because of shunt capacitance, for instance, tube and wiring capacities. The singing tendency may become particularly troublesome when the amplifier is called upon to transmit wide frequency bands extending to very high frequencies, for example.

In its specific aspect mentioned above, the invention is a negative feedback amplifier including a screen grid tube having in its screen grid lead a frequency selective impedance that causes the screen grid to assume potentials which produce in the amplifier, as indicated hereinafter, phase shift and gain reduction that reduce the singing tendency without unduly affecting operation of the amplifier deleteriously in the utilized frequency range.

As indicated above, loop gain and loop phase shift present important limitations in operation of feedback amplifiers, especially the loop gain and loop phase shift at low and high frequencies in operation of wide band negative feedback amplifiers for reducing modulation or distortion by feedback action.

An object of the invention is to so control the loop gain and loop phase shifts as to reduce singing tendency or to increase the distortion suppression obtainable in such amplifiers, or both.

Other objects and aspects of the invention will be apparent from the following description and claims.

In the accompanying drawings, Fig. 1 is a circuit diagram of an amplifier embodying the specific aspect of the invention referred to above, with impedances in its screen grid circuits shown as generalized impedances;

Fig. 2 is a circuit diagram facilitating explanation of the action of the impedances;

Figs. 3, 4, 5 and 6 show examples of specific forms the impedances may have; and,

Figs. 3A and 3B are vector diagrams facilitating explanation of the action of the impedances shown in Figs. 3, 4, 5 and 6.

In Fig. 1 a network amplifier amplifies waves received by input transformer T from line or circuit L and transmits the amplified waves through output transformer T' to line or circuit L'. The amplifier comprises a forwardly transmitting path shown by way of example as including three impedance coupled screen grid vacuum tubes 1, 2 and 3 in tandem, and comprises a feedback path F which may, if desired, include a network N for transmission control.

The amplifier may be of the general type referred to above as disclosed in the above mentioned copending application, Serial No. 606,871, in which, over the range of transmitted frequencies (for example 4 kilocycles to 40 kilocycles, or 50 kilocycles to 500 kilocycles) loop gain is much greater than unity and in which waves, including fundamental and distortion waves of the range of transmitted frequencies, are so fed back as to reduce the amplifier gain below its value for operation without feedback, in order to reduce distortion correspondingly and render the gain stability greater than for operation without feedback.

The network N may be, for instance, an attenuation equalizer, with its attenuation-frequency characteristic like that of the cable or line in which the amplifier is connected; for then, as explained in the above mentioned copending application 606,871 or British Patent 371,887, the amplifier will equalize the line attenuation.

By way of example, tubes 1 and 2 are shown as of the heater type, a battery A is shown as supplying filament heating current for all of the tubes, a battery B is shown as supplying space current for all of the tubes, a battery 5 is shown as supplying negative biasing potential for the control grid of tube 3, and cathode lead resistors 6 and 7 are shown as supplying negative biasing potentials for the control grids of tubes 1 and 2, respectively.

Each of the two interstage coupling circuits includes a plate retard or choke coil 10, a stopping condenser 11 and a grid leak resistor 12.

Impedance may be connected in the screen circuit of one or more of the tubes to control the phase or amplitude, or both, of waves, transmitted by the tube. For instance, each tube is shown as having impedances Z_1 , Z_2 , and Z_3 in its screen circuit, and these impedances can be used for frequency selective phase or amplitude control, for example, to reduce singing tendency of the amplifier.

Fig. 2 shows a screen grid vacuum tube circuit such as that of each stage of Fig. 1. When each of the three impedances Z_1 , Z_2 , and Z_3 is zero, the tube circuit is a normal screen grid tube circuit and the voltage V across the load impedance Z_0 is the same as if the tube were a three element tube, and so is given by the equation:

$$-V = \mu' e \frac{Z_0}{R_o + Z_0},$$

the symbols μ' , e and R_o , and also the symbols μ_1 , R_s , E and μ_2 which are referred to below, having the significance indicated in Fig. 2, μ' , μ_1 and μ_2 representing the tube amplification constants, respectively from control grid to plate circuit, control grid to screen grid circuit, and screen grid to plate circuit. When each of the two impedances Z_2 and Z_3 is zero, and Z_1 is not zero,

$$-E = \mu_1 e \frac{Z_s}{R_s + Z_s},$$

and therefore

$$-V = \mu' e \frac{Z_0}{R_o + Z_0} - \mu_2 \mu_1 e \frac{Z_s}{R_s + Z_s} \cdot \frac{Z_0}{R_o + Z_0}. \quad (1)$$

For ideal screening action, (in which $\mu' = \mu_1 \mu_2$ and $R_s = R_o$), Equation (1) becomes:

$$-V = \mu' e \frac{Z_0}{R_o + Z_0} - \mu' e \frac{Z_s}{R_o + Z_s} \cdot \frac{Z_0}{R_o + Z_0},$$

whence

$$\begin{aligned} -V &= \mu' e \frac{Z_0}{R_o + Z_0} \left(1 - \frac{Z_s}{R_o + Z_s} \right) \\ &= \mu' e \frac{Z_0}{R_o + Z_s} \cdot \frac{R_o}{R_o + Z_s}. \end{aligned}$$

The phase angle of the expression

$$\frac{R_o}{R_o + Z_s},$$

in the last equation is the amount of phase shift introduced by the action of the screen grid; and the absolute magnitude of that expression is

the change in amplification ratio introduced by the action of the screen grid.

If R_o is not equal to R_s and μ' is not equal to $\mu_1 \mu_2$, Equation (1) is used in determining V . It has been found by measurements that μ' is very nearly equal to $\mu_1 \mu_2$, but R_s is much smaller than R_o , (about one-tenth of the value of R_o). This is advantageous, in that the smaller the value of R_s the greater is the percentage of $\mu_1 \mu_2$ across Z_1 and therefore the more effectively does the screen grid control the amplification of the circuit.

When none of the impedances Z_1 , Z_2 and Z_3 is restricted to zero value, instead of Equation (1), we have

$$-V = \mu' e \frac{Z_0}{R_o + Z_0} - \mu_1 \mu_2 e \left[\frac{Z_1 (Z_2 + Z_3) + Z_2 Z_3}{(R_o + Z_1) (Z_2 + Z_3) + Z_2 Z_3} \right] \frac{Z_0}{R_o + Z_0}. \quad (2)$$

In feedback amplifiers of the general type shown in Fig. 1, the loop phase shift introduced by the elements other than the tubes commonly changes with frequency from large negative values at frequencies far below the utilized frequency range, to large positive values at frequencies far above the utilized range. For example, the phase shift may be negative for low frequencies in the transmitting range and below, and positive for high frequencies in the transmitting range and above. As indicated above, this phase shift may produce objectionable effects, notably singing around the loop. Compensation for this phase shift and avoidance of the singing or other objectionable effects, can be accomplished by connecting impedance in the screen circuit of one or more of the vacuum tube stages.

For example, Fig. 3 shows an inductance coil 20 connected as impedance Z_1 in the screen lead of a tube. Inductance in the screen lead introduces positive phase shift in waves transmitted through (amplified by) the tube, and capacity in the screen lead introduces negative phase shift in those waves. Therefore, the inductance of coil 20 can be made to compensate for deleterious negative phase shift at the low frequencies; and moreover, the coil 20 can be made to compensate for deleterious positive phase shift at the high frequencies, by virtue of its capacitive reactance above its resonance frequency, the coil being designed to have its resonance frequency below the frequencies at which it is to compensate for the positive phase shift. Any phase shifts introduced by the coil at frequencies other than the frequencies at which the coil reduces deleterious phase shift, need not be objectionable. For example, they can be made to occur in a frequency region where they are tolerable from the standpoint of avoiding singing around the feedback loop. The feedback action of the amplifier reduces any variation of the amplifier gain with frequency introduced by the coil 20 in the utilized frequency band, where μ_2 for the feedback amplifier is large compared to unity. The inherent capacity of coil 20 is indicated at 20'. If desired it can be augmented by additional capacity in the form of a separate condenser.

Fig. 3A shows the relation between $\mu' e$ and $\mu_2 E$, for the low frequencies, for which the coil 20 acts as an inductance.

Fig. 3B shows the relation between μe and R

for the high frequencies, for which the coil 20 acts as a capacity.

In Fig. 3A the addition of $\mu_2 E$ to $\mu'e$ has resulted in a voltage R which lags $\mu'e$ by an angle θ ; and in Fig. 3B the addition of $\mu_2 E$ to $\mu'e$ has resulted in a voltage R which leads $\mu'e$ by an angle θ .

Feedback amplifiers of the general type shown in Fig. 1 sometimes tend to sing at low frequencies 10 in the utilized frequency range, or at lower frequencies, for example frequencies far below the utilized range. For instance in the case of a 4 kilocycle to 40 kilocycle amplifier, singing tendency may be troublesome in the lower part of 15 the operating frequency band or at a frequency such as 200 cycles, or at so-called "thump frequencies," say below 10 cycles per second, or may be troublesome at any of these frequencies. The 20 low frequency singing can be prevented by connecting a capacity and a resistance in parallel, in the screen lead of one or more stages.

For example, Fig. 4 shows a capacity 30 and a 25 resistance 31 in parallel, forming an impedance Z_1 in the screen lead of a tube. At high frequencies, the condenser 30 is a short circuit, so Z_1 is zero and the tube circuit acts as a normal 30 screen grid tube circuit. Fig. 3B can serve to indicate the action of this circuit at the low frequencies, the amplification ratio and the gain 35 being reduced by the action of Z_1 as indicated by the fact that R is shown shorter than $\mu'e$. The phase shift introduced by the action Z_1 is negative, which is likely to be of the wrong sign for utilization to compensate for deleterious phase 40 shift in the loop; but the phase shift introduced by Z_1 can be made to have its maximum at a frequency above the low frequencies at which the singing tendency is troublesome and be low at the latter frequencies whereas the gain reduction introduced by the impedance Z_1 can at the 45 same time be made large over the frequency range of the latter frequencies and small for higher frequencies. With decreasing frequency, as the reactance of the capacity 30 becomes very high so that the effect of the capacity is substantially negligible, resistance 31 is highly effective in reducing gain. Therefore the capacity and resistance can be used to reduce the loop gain of a feedback amplifier below zero before increase 50 of loop phase shift with frequency decrease causes the loop phase shift to reach a potential singing value of zero or a multiple of 360 degrees.

Fig. 5 shows impedance Z_1 combining the 55 impedances Z_1 of Figs. 3 and 4, to obtain the advantages of each in the same tube circuit. The coil 20 can be made effectively a short circuit or of zero impedance to low frequencies for which resistance 31 is used to reduce gain; and the condenser 30 can be made to short circuit resistance 31 for frequencies at and below those for which coil 20 is used to control phase shift.

Any of the circuits of Figs. 3, 4 or 5 can be employed in any of the stages of an amplifier such 65 as that of Fig. 1. For example, the circuits of Figs. 3, 4 and 5 may be used in stages 1, 2 and 3, respectively of Fig. 1. Various forms of impedances may be used for the elements Z_1 , Z_2 and Z_3 in Fig. 1. Examples have been given of forms 70 that impedances Z_1 can have; and Fig. 6 shows, by way of example, forms which impedances Z_2 and Z_3 may take. In Fig. 6, Z_3 is a resistance and Z_2 is a condenser. These two elements may 75 be for instance a noise filter, the capacity of Z_2

being sufficient to make the value of Z_2 substantially zero or negligibly small.

What is claimed is:

1. A wave translating system comprising a vacuum tube having a control grid and an auxiliary grid and auxiliary grid circuit, a capacitative load circuit for said tube, the capacitive character of said load circuit causing the component of the voltage across said load circuit that is due only to the voltage on the control grid to be retarded 10 in phase with respect to the control grid voltage, and means comprising impedance in said auxiliary grid circuit adapted to produce on said auxiliary grid a voltage advancing the phase of the voltage across said load circuit with respect 15 to the control grid voltage and thereby compensating for the retardation of the load circuit voltage, with respect to the control grid voltage, caused by the capacitive character of said load circuit. 20

2. A wave amplifying system comprising an amplifier including a vacuum tube having a screen grid, means forming with said amplifier a closed feedback loop producing negative feedback therein for rendering modulation therein 25 less than without feedback, and means producing potentials on said grid that reduce tendency of the system to sing around said loop.

3. A wave amplifying system comprising an amplifier including a vacuum tube having a screen grid and a screen grid lead, means forming with said amplifier a closed feedback loop producing negative feedback therein in the utilized frequency band, a source of unidirectional voltage in said lead for producing positive potential 35 on said screen grid, and impedance, comprising reactance, connected in series with said source in said lead and adapted to cause voltage drop across said impedance resulting from current flow in said impedance to produce screen grid 40 potentials reducing tendency of the system to sing around said loop outside the utilized frequency range. 45

4. A wave amplifying system comprising an amplifier including a vacuum tube having a screen grid and a screen grid lead, means forming with said amplifier a closed feedback loop producing negative feedback therein for a given frequency range, and frequency selective means in said lead adapted to produce in said loop a 50 component of loop phase shift so related to the remaining loop phase shift as to reduce tendency of the system to sing around said loop outside said frequency range.

5. A wave amplifying system comprising an amplifier including a vacuum tube having a cathode, a screen grid and a screen grid lead, means forming with said amplifier a closed feedback loop producing negative feedback therein for a given frequency range, and a source of unidirectional voltage and frequency selective means in serial relation in said lead for reducing the gain 60 of said amplifier at frequencies outside said frequency range.

6. A wave amplifying system comprising an amplifier including a vacuum tube having a screen grid and a screen grid lead, means forming with said amplifier a closed feedback loop producing negative feedback therein for a given frequency range, and a source of unidirectional 65 voltage and frequency selective means in serial relation in said lead for producing gain reduction and phase shift in said amplifier that reduce tendency of the system to sing around said loop at frequencies outside said frequency range. 75

7. A wave translating system comprising an amplifier including a vacuum tube having a screen grid and a screen grid lead, means forming with said amplifier a closed feedback loop producing negative feedback therein in the utilized frequency band, and impedance in said lead

to reduce tendency of the system to sing around said loop, said impedance comprising a reactance including an inductance coil and a condenser in serial relation therein and a resistor connected across a portion of said reactance.

5 ALPHONS V. WURMSER.
